(57) **CLAIM**

The ornamental design for a laminate hard surface reducer, as shown and described.

DESCRIPTION

FIG. 1 is a top perspective view of the laminate hard surface reducer;

FIG. 2 is a bottom perspective view of the laminate hard surface reducer;

FIG. 3 is a bottom view of the laminate hard surface reducer; and,

FIG. 4 is an end view of the laminate hard surface reducer, the opposite end view being a mirror image thereof.

It should be understood that the laminate hard surface reducer of the present drawings is an indeterminate length, which may be cut to a length as needed; the length shown in FIGS. 1-4 is for convenience of illustration.
